UNITED STATES PATENT OFFICE.

SAMUEL S. PETERSON, OF WYANDOTTE, KANSAS, ASSIGNOR OF ONE-HALF
TO WILLIAM C. DUVALL, OF KANSAS CITY, MISSOURI.

SLIDING-DOOR LOCK.

SPECIFICATION forming part of Letters Patent No. 293,593, dated February 12, 1884.

Application filed November 13, 1883. (Model.)

To all whom it may concern:

Be it known that I, SAMUEL S. PETERSON, of Wyandotte, in the county of Wyandotte, State of Kansas, have invented a new and useful Improvement in Fastenings for Car-Doors, of which the following is a full, clear, and exact description, reference being had to the accompanying drawings, making a part of this specification, in which—

10 Figure 1 shows the front elevation of a freight-car door with my improved fastenings attached and the door sealed. Fig. 2 shows the same with the door open. Fig. 3 is a section through *x x* of Fig. 1. Fig. 4 are details 15 to be referred to.

My invention relates to that class of fastenings which are used on freight-cars that require to be fastened during transportation; and it consists of the combination of devices, 20 as hereinafter explained and claimed.

In order to enable others skilled in the art to make and use my invention, I will proceed to describe the exact manner in which I have carried it out.

25 In the drawings, A represents the side of a freight-car provided with the door B, hung on ways and caused to slide in the usual well-known manner. In the side of the car, and flush therewith, I secure the metal block C.

30 This block is provided with the vertical dovetailed slot or groove D, the opening of the slot flaring near its top to receive the dovetailed tenon on the block E, whereby the block E is readily and easily attached to and detached 35 from the block C. When the block E is in position for use, as shown in Fig. 1, its edge fits snugly up to the edge of the door B, whereby the door is held steadily in position when closed. The outer face or edge of the block E is nar-

rowed, so as to receive the hasp F, as shown in 40 Fig 1. Near the edge of the block is a perforation, G, through which passes the key H, for locking the hasp F on the block E, and the lower end of the key H is perforated to receive the usual seal applied to freight-car fastenings. It 45 is evident that this seal might be applied to the block E at the perforation G, and thus secure the hasp in place; but the friction of the hasp, caused by the shaking of the cars, would have a tendency to damage the seal, if not to destroy it altogether; but when the seal is attached to the lower end of the key H it is evident that the seal is free from all such danger. I secure the key H and block E by chains, in order to avoid the possibility of their being 55 lost or mislaid.

The operation of my improved fastening is as follows: The door B having been closed, the block E is slipped into position in the slot D, and the hasp E is placed in position over the 60 block. The key H is then dropped into the perforation G and secured by a seal in any of the well-known ways.

Having thus described my invention, what I claim as new, and desire to secure by Letters 65 Patent, is—

In a car-door fastening, the grooved metal block C, provided with the dovetailed groove D, and the metal block E, provided with a dovetailed tenon fitting into the dovetailed groove 70 D, and perforated to receive a slotted key or seal, H, in combination with the hasp F, pivotally secured to the car-door, all substantially as shown, and for the purposes described.

SAMUEL S. PETERSON.
